CONVEYER SYSTEM FOR HANDLING
PICKER LAPSConway L. Still, Chester, S. C., assignor to The
Springs Cotton Mills, Inc., a corporation of
South Carolina

Application December 21, 1949, Serial No. 134,219

6 Claims. (Cl. 214—60)

1

This invention relates generally to conveyor systems, and more especially to a conveyor system adapted particularly for handling picker laps and arranged for use in maintaining a supply of picker laps at a battery of cards.

In textile manufacturing operations, the raw stock is commonly fed at an early stage through a picker which works the fiber stock being processed into a lap. This lap is wound in roll form as it issues from the picker for transfer to subsequent processing operations, and the rolled lap obtained in this manner is referred to as a "picker lap." Usually these picker laps are transferred to a card for further processing at which the lap is unwound for feeding through the card.

It is common practice to arrange a number of these cards in a battery for processing the picker laps, and each card is characteristically arranged with a lap stand for supporting a picker lap in position for unwinding and feeding through the card. These lap stands consist essentially of a frame structure formed with two vertical end plates which are spaced to allow disposition of the picker lap between them, and which are formed with a vertical slot to receive and support the ends of the metal lap pins on which the picker laps are wound at the picker.

With a battery of cards arranged in this manner, there is a considerable handling problem involved in maintaining a supply of picker laps at the cards. Heretofore this has usually been done by hauling the picker laps individually to the cards, and while special trucks and the like have been adapted for this purpose, the methods previously employed have characteristically involved a substantial amount of manual handling, which has been undesirable not only because this manual handling must be supervised carefully in order to avoid damage to the picker laps, but also because these picker laps are bulky and unwieldy in form so that it has been difficult to handle them efficiently by the predominantly manual methods heretofore in use.

According to the present invention a conveyor system is provided by which a supply of picker laps can be maintained at a battery of cards automatically without any manual handling at all. Briefly described, the picker lap conveyor system of the present invention comprises a receiving rack arranged adjacent the lap stand of each card in the battery to be supplied, an overhead conveyor means spaced above the conveyor racks, and at least one picker lap carrying frame disposed for travel on the overhead conveyor means. The receiving racks arranged adjacent

2

the lap stands comprise a cradle adapted to receive and support a picker lap, which cradle is supported on yieldable legs or columns that normally position the cradle at a raised position so that a trip arm associated with the cradle is disposed for actuating the carrying frame to transfer a picker lap to the cradle. Upon this transfer of the picker lap to the cradle, the yieldable supporting legs allow the cradle to shift to a lowered or depressed position under the load of the picker lap so that the trip arm is displaced from the path of the carrying frame as long as the cradle is loaded with a picker lap, and the conveyor system is thereby adapted for delivering a picker lap selectively to any of the receiving racks whenever they are empty.

The picker lap conveyor system of the present invention is described further below in connection with the accompanying drawings, in which:

20 Fig. 1 is a fragmentary elevation of a picker lap conveyor system arranged according to the present invention;

25 Fig. 2 is an enlarged detail of the picker lap carrying frame employed in the conveyor system shown in Fig. 1;

Fig. 3 is a side view of the picker lap carrying frame as seen from the left in Fig. 2;

30 Fig. 4 is a fragmentary detail taken substantially on the line 4—4 in Fig. 2;

Fig. 5 is a left side view corresponding generally to Fig. 3 but showing the carrying frame disposed for releasing a picker lap onto a receiving rack;

35 Fig. 6 is a section taken substantially on the line 6—6 in Fig. 1, and illustrating the arrangement of the receiving racks in relation to the picker lap carrying frame; and

40 Fig. 7 is a further side view of the picker lap carrying frame corresponding generally to Fig. 3, but including a fragmentary representation of the receiving rack, and illustrating a modification by which further selective actuation of the carrying frames may be obtained in delivering picker laps to the receiving racks.

45 As illustrated in Fig. 1 of the drawing, the previously mentioned receiving racks of the picker lap conveyor system of the present invention are indicated generally by the reference numeral 10; the overhead conveyor means by the reference numeral 12; and the picker lap carrying frames by the reference numeral 14. A receiving rack 10 is shown in Fig. 1 disposed adjacent each lap stand S of a battery of cards to be supplied with picker laps L, such as are shown disposed in the 50 lap stands S, supported in reserve on the re-

ceiving racks 10, and being delivered by the carrying frames 14, as will be described more in detail presently.

The receiving racks 10 are preferably associated directly with the lap stands S as indicated in Fig. 1. As shown, the receiving racks 10 each comprise a pair of supporting legs 16 that are fitted with foot plates 18 for attachment at the base of the lap stands S, and are braced adjacent their upper ends by brackets 20 extending from the upper portion of the lap stands S. The supporting legs 16 are tubular in form (compare Fig. 6), and each of them slidably receives at its upper end a shaft member 22 that bottoms on a compression spring 24 contained in the lower portion of each supporting leg 16.

The shaft members 22 are formed with a longitudinal groove or slot for a portion of their length as indicated at 26, and the tubular supporting legs 16 are each fitted with a pin 28 extending inwardly for disposition in the groove 22 to provide a limiting stop determining the extent to which the shaft members 22 may be raised under the pressure of the springs 24, as indicated in full lines in Fig. 6. The upper ends of the shaft members 22 are further formed with flanges as at 30, and these flanges 30 bottom on the upper ends of the supporting legs 16 to determine the extent of allowable downward movement of the shaft members 22 against the pressure of springs 24. The shaft members 22 associated with each pair of the supporting legs 16 at the lap stands S carry a crossbar 32 at their upper ends, and this crossbar 32 in turn supports a wooden-slat type cradle unit 34, together with an upstanding trip arm as at 36.

The overhead conveyor means 12 arranged above the receiving racks 10 may be of any conventional form adapted for supporting material handling gear, such as the picker lap carrying frames 14, which are suspended from the conveyor means 12 in any suitable manner such as by hanger straps as at 38, comprise a hanger yoke 40 formed with leg portions adapted to straddle a picker lap L lengthwise or longitudinally (compare Fig. 2). Each of the leg portions of these hanger yokes 40 support plate elements 42 and 44 for rotation. The right hand plate element 42, as seen in Fig. 2, is mounted for rotation on the hanger yoke 40 by a simple pivot stud as at 46, while the left hand plate element 44 is mounted for rotation on a specially formed pivot stud 48 as will be explained in further detail below. Both of the plate elements 42 and 44 carried by the hanger yoke 40 are connected by a bracket 50 by which they are caused to rotate together. Also, each of the plate elements 42 and 44 is formed with a marginal notch as at 42' and 44' for receiving the ends of a lap pin P and thereby carrying a picker lap L wound on the lap pin P.

The previously mentioned specially formed pivot stud 48 provided for the plate member 44 is arranged with a portion of enlarged diameter, as shown, that extends from the plate element 44 through the hanger yoke 40 in the nature of a journal and terminates in a flange 52 adapted by lugs 54 to form a pivot support as at 56 for a lever member 58, which is pivotably supported by the lugs 54 intermediately of its ends and extends transversely with respect to the plate element 44. A suitable keeper 60 is mounted on the leg portion of the hanger yoke 40 adjacent the plate element 44, and a spring element 62 is carried by the flange 52 of the pivot stud 48 for

normally positioning one extending end 58' of the locking lever 58 for engagement with the keeper 60 to retain the plate element 44, and consequently the plate element 42, against rotation.

The lever member 58 is arranged transversely in relation to the plate element 44 so that when its extending end 58' is in engagement with the keeper 60, the marginal notches 42' and 44' in the plate elements 42 and 44 are disposed upwardly for carrying a picker lap L (compare Figs. 3 and 4). It should be noted, however, that when the notches 42' and 44' are in this position they are still displaced from vertical alignment with the axis of rotation of the plate elements 42 and 44 so that the picker lap L is carried by the plate elements 42 and 44 as an off-center load that exerts a turning movement on them. To keep the hanger yoke 40 in balance when a picker lap is being carried in this manner, the depending ends of its leg portions are biased so as to place the seat of the notches 42' and 44' in substantial vertical alignment with the hanger yoke 40 when they are disposed for carrying a picker lap L. The extending end 58' of the lever member 58 is similarly biased so that when it is in engagement with the keeper 60, the other extending end of the lever 58 is disposed in a position depending vertically from the hanger yoke 40.

In operation, the picker laps L are loaded in the carrying frames 14, as just described above, at a suitable accumulating station for the picker laps, which may suitably be arranged adjacent the pickers at which the laps are formed, and the loaded picker laps L are carried in this manner on the conveyor means 12 to the card battery. At this point the loaded carrying frames 14 will be directed above the receiving racks 10, as illustrated in Fig. 1, and assuming initially that none of the receiving racks 10 are loaded, each of them will be disposed in raised position by the compression springs 24 contained in the supporting legs 16. At this raised position the trip arms 36 are arranged to be situated in the path of travel of the carrying frames 14 for engaging the depending end of the lever member 58 (compare Figs. 1 and 6). This engagement by the trip arm 36 causes pivoting of the locking lever 58 to release its biased extending end 58' from the keeper 60 (compare Fig. 2), and when this happens the plate elements 42 and 44 are released for rotation under the off-center weight of the picker lap L, as mentioned above. The plate elements 42 and 44 will accordingly rotate in the hanger yoke 40 to discharge the lap pin P from the marginal notches 42' and 44' (compare Fig. 5), and transfer the picker lap L to the cradle 34 of the receiving rack 10, a stop pin 64 being arranged on the plate element 44 to limit the extent of rotation suitably as this occurs so that the connecting bracket 50, which unbalances the plate elements 42 and 44 and will thereby maintain them at the discharging position, will assume and will cause the lever member 58 to assume a horizontally extending position as shown in Fig. 5. This disposition of the carrying frame 14 after a picker lap L has been discharged displaces the lever member 58 so that it is entirely out of position for contact with the trip arm 36 of any succeeding receiving rack 10, and the empty carrying frames 14 may accordingly travel freely on the conveyor means 12 for return to the picker lap accumulating station where the lever member 58 may be reset to engage the keeper 60 and thereby dispose the carrying frame 14 for reloading with another picker lap L.

The weight of the picker lap L transferred to the receiving rack 10, as described above, will cause telescoping of the shaft members 22 into the supporting legs 16 against the pressure of the spring 24 until the shaft member flanges 30 bottom on the upper ends of the supporting legs 16 and the cradle 34 and trip arm 36 are thereby shifted to a lowered or depressed position that is displaced from the path of the carrying frames 14 as long as the cradle 34 remains loaded with a picker lap L. Other loaded carrying frames 14 may accordingly also travel freely on the conveyor means 12 above any loaded receiving racks 10 to carry further picker laps L for delivery to unloaded receiving racks 10 beyond. Each previously loaded receiving rack 10, however, will return to raised position for reloading whenever the reserve picker lap L it carries is removed for use, and the conveyor system of the present invention may thus be operated in a continuous manner for maintaining a supply of picker laps automatically at the battery of cards it serves.

Fig. 7 of the drawing illustrates a further modification which may be employed according to the present invention for rendering the actuation of the carrying frames 14 additionally selective in delivering picker laps L to the receiving racks 10. There are instances, for example, when the picker laps L being delivered to a battery of cards will consist of different blends, and when it will accordingly be desired to deliver laps of each blend exclusively to particular cards of the battery. To provide more fully for a situation of this sort, the lever members 58 of the carrying frames 14 may be fitted at their depending ends with a transverse arm 66 formed with a plurality of mounting positions, as at a, b, c, and d, for carrying a depending finger 68, and the trip arms 36 of the receiving racks 10 may likewise be fitted with a similar transverse arm 70 formed with corresponding mounting positions, as at a', b', c', and d', for carrying an upstanding target 72. With this arrangement it is possible to set the fingers 66 on certain carrying frames 14, used to carry laps L of a particular blend, at a given mounting position a, and at the cards selected for precessing this blend of lap L to arrange the targets 72 on the receiving racks 10 at the corresponding mounting position a', so that the laps L loaded in these carrying frames 14 will be delivered only at the receiving racks 10 for the cards selected, and so on for other blends as required.

I claim:

1. A picker lap conveyor system for maintaining a supply of picker laps at a battery of cards, comprising a receiving rack arranged adjacent the lap stand of each card in said battery, an overhead conveyor means spaced above said receiving racks, and at least one picker lap carrying frame disposed for travel on said overhead conveyor means, said receiving racks comprising a cradle, yieldable supporting means for said cradle, and a trip arm associated with said cradle, said yieldable supporting means normally positioning said cradle at a raised position with said trip arm disposed for actuating said carrying frame to transfer a picker lap to said cradle, but allowing shifting of said cradle to a depressed position under the load of a picker lap whereby said trip arm is displaced from the path of said carrying frame as long as said cradle is loaded with a picker lap.

2. A picker lap conveyor system for maintaining a supply of picker laps at a battery of cards,

comprising a receiving rack arranged adjacent the lap stand of each card in said battery, an overhead conveyor means spaced above said receiving racks, and at least one picker lap carrying frame disposed for travel on said overhead conveyor means, said picker lap carrying frame comprising a hanger yoke adapted to straddle a picker lap, a plate element mounted for rotation on each leg of said hanger yoke, each of said plate elements being formed with a marginal notch for receiving the ends of a lap pin and thereby carry a picker lap wound thereon, releasable means normally positioned for retaining said plate elements against rotation with said marginal notches disposed for carrying a picker lap, but upon release allowing rotation of said plate elements for transferring the picker lap to one of said receiving racks, and said receiving racks comprising a cradle, vertically yieldable supporting means for said cradle, and a trip arm extending vertically upward from said cradle, said yieldable supporting means normally positioning said cradle at a raised position with said trip arm disposed in the path of said carrying frame for releasing said plate element retaining means, but said yieldable supporting means allowing shifting of said receiving rack cradle to a depressed position under the load of a transferred picker lap whereby said trip arm is displaced from the path of said carrying frame as long as said cradle is loaded with a picker lap.

3. A picker lap conveyor system for maintaining a supply of picker laps at a battery of cards, comprising a receiving rack arranged adjacent the lap stand of each card in said battery, an overhead conveyor means spaced above said receiving racks, and at least one picker lap carrying frame disposed for travel on said overhead conveyor means, said picker lap carrying frame comprising a hanger yoke adapted to straddle a picker lap, a plate element mounted for rotation on each leg of said hanger yoke, a bracket connecting said plate elements for rotation together, each of said plate elements being formed with a marginal notch for receiving the ends of a lap pin and thereby carrying a picker lap wound thereon, means including a lever member pivoted on one of said plate elements and extending transversely thereof, said lever member being yieldably positioned for normally retaining said plate elements against rotation with said marginal notches disposed for carrying a picker lap and one end of said lever member depending vertically from said hanger yoke when said plate elements are retained against rotation, and said receiving racks each comprising trip means for pivoting said locking lever and thereby releasing said plate elements for rotation under the weight of a picker lap to transfer the picker lap to a receiving rack.

4. A picker lap conveyor system for maintaining a supply of picker laps at a battery of cards, comprising a receiving rack arranged adjacent the lap stand of each card in said battery, an overhead conveyor means spaced above said receiving racks, and at least one picker lap carrying frame disposed for travel on said overhead conveyor means, said picker lap carrying frame comprising a hanger yoke adapted to straddle a picker lap, a plate element mounted for rotation on each leg of said hanger yoke, a bracket connecting said plate elements for rotation together, each of said plate elements being formed with a marginal notch for receiving the ends of a lap pin and thereby carrying a picker

lap wound thereon, a keeper arranged on one leg of said hanger yoke, a locking lever pivoted intermediate its ends on the plate element carried by the same leg of said hanger yoke and extending transversely of said plate element, yieldable means carried by said plate element for normally positioning one extending end of said locking lever for engagement with said keeper to retain said plate elements against rotation with said marginal notches disposed for carrying a picker lap, and with the other extending end of said locking lever depending vertically from said hanger yoke, and each of said receiving racks comprising trip means for engaging the depending end of said locking lever and thereby actuating said carrying frame to transfer a picker lap selectively to one of said receiving racks.

5. A picker lap conveyor system for maintaining a supply of picker laps at a battery of cards, comprising a receiving rack arranged adjacent the lap stand of each card in said battery, an overhead conveyor means spaced above said receiving racks, and at least one picker lap carrying frame disposed for travel on said overhead conveyor means, said picker lap carrying frame comprising a hanger yoke formed with leg portions adapted to straddle a picker lap longitudinally, a plate element mounted for rotation on each leg portion of said hanger yoke, a bracket connecting said plate elements for rotation together, each of said plate elements being formed with a marginal notch for receiving the ends of a lap pin and thereby carrying a picker lap wound thereon, a lever member pivoted intermediate its ends on one of said plate elements and extending transversely thereof, a keeper arranged on said hanger yoke, yieldable means carried by said plate element for normally positioning one extending end of said lever member for engagement with said keeper to retain said plate elements against rotation with said marginal notches displaced from vertical alignment with the axis of rotation of said plate elements but disposed upwardly for carrying a picker lap, and with the other extending end of said locking lever depending vertically from said hanger yoke, and each of said receiving racks comprising a cradle, yieldable supporting means for said cradle, and an upstanding trip arm associated with said cradle, said yieldable supporting means normally positioning said cradle at a raised position with said trip arm disposed in the path of travel of said carrying frame for engaging the depending end of said locking lever and thereby pivoting said lever free of said keeper to release said plate elements for rotation to transfer a picker lap to said receiving rack, and said yieldable supporting means allowing shifting of said cradle to a depressed position under the load of a picker lap whereby said trip arm is displaced from the path of said carrying frame as long as said cradle is loaded with a picker lap.

6. A picker lap conveyor system for maintaining a supply of picker laps at a battery of cards, comprising a receiving rack arranged adjacent the lap stand of each card in said battery, an overhead conveyor means spaced above said receiving racks, and a plurality of picker lap carrying frames disposed for travel on said overhead conveyor means, each of said picker lap carrying frames comprising a hanger yoke formed with leg portions adapted to straddle a picker lap longitudinally, means carried on said hanger yoke for releasably supporting a picker lap, a lever member pivotably associated with said supporting means, said lever member being yieldably positioned with one extending end normally disposed for engagement with said hanger yoke and thereby preventing release of a picker lap supported by said means, and with the other extending end of said lever member depending from said hanger yoke, and the depending end of said lever member being fitted with a transverse arm member formed to provide a plurality of laterally spaced mounting positions for an associated depending finger element, and each of said receiving racks comprising a cradle, yieldable supporting means for said cradle, and an upstanding trip arm associated with said cradle, said trip arm being likewise fitted at its upper end with a second transverse arm similar to said first mentioned transverse arm at the depending end of said lever member, and said second transverse arm being formed to provide corresponding mounting positions for an associated upstanding target element, said yieldable supporting means normally positioning said cradle at a raised position with said trip arm arranged to dispose said target element in the path of travel of said carrying frames for engaging a finger element carried in a corresponding mounting position at the depending end of said lever member and thereby pivoting said lever member free of said hanger yoke to allow release of a picker lap from said supporting means for transfer to said receiving rack, and said yieldable supporting means allowing shifting of said cradle to a depressed position under the load of a picker lap whereby the target element on said trip arm is displaced from the path of said carrying frame as long as said cradle is loaded with a picker lap.
